H. R. CAMPBELL.
BRIDGE WARNING INDICATOR.
APPLICATION FILED FEB. 17, 1913.

1,098,781.

Patented June 2, 1914.

UNITED STATES PATENT OFFICE.

HERBERT R. CAMPBELL, OF PATERSON, NEW JERSEY.

BRIDGE-WARNING INDICATOR.

1,098,781.

Specification of Letters Patent.

Patented June 2, 1914.

Application filed February 17, 1913. Serial No. 748,839.

To all whom it may concern:

Be it known that I, HERBERT R. CAMPBELL, a citizen of the United States, residing at Paterson, in the county of Passaic and State of New Jersey, have invented certain new and useful Improvements in Bridge-Warning Indicators, of which the following is a specification.

This invention consists in certain improvements in bridge-warning indicators and the like whereby is produced an indicator which, while simple, strong and durable in construction, is capable of being readily installed and kept in working order without subjecting the workmen to danger from passing trains and which is so constructed that should its tell-tale-carrying arm become partially or wholly detached from the pole said arm must fall to a position where it is entirely clear of the traffic.

In the accompanying drawing, Figure 1 is a view showing the improved bridge-warning indicator in front elevation; Fig. 2 is a view on a somewhat larger scale showing the main parts of the device principally in front elevation, but partly in section; Fig. 3 is a vertical sectional view of the head of the pole or upright; and, Fig. 4 is a vertical sectional view in a plane at right angles to that of Fig. 3 and taken just to the right of the pivot for the arm as seen in Figs. 1 and 2.

The upright *a* is preferably a pole of the well-known hollow telescoped construction. Into the upper end of this pole is removably fitted the stem *b* of a head *c* which may be kept from turning therein by the removable pin *d* or otherwise. The pole may be set in a bed of concrete *e* or the like beside the roadbed *f* shown in Fig. 1, and the construction of the head *c* is preferably such that it overhangs at the side of the pole which is next to the roadbed, as at *c'*. The head *c* includes two spaced walls or cheeks *g*, thus giving it a bifurcated form, the slot or space *h* between its walls *g* being open not only upwardly and laterally in opposite directions but, in respect to the part *c'* of the head, downwardly. Through the walls *g* and in the part *c'* of the head is passed a horizontal bolt *i* having a retaining nut *j*.

The arm *k* is a strip of angle iron which is straight for the greater part of its length and has its remaining portion bent to an angle of about 45° in such manner that the wall *k'* of the strip remains in the same

plane as before the bending was effected. By forming the arm of angle iron, relatively light material may be used and to reinforce the arm at the bend therein I rivet to the wall *k'* thereof a gusset *l* formed to fit the angle of the wall *k''* of the arm, such gusset also affording an increased bearing surface for the pivotal movement of the arm, as will appear.

The arm *k*, whose wall *k'* is fitted into the slot *h* of the head *c* and is penetrated by and thus has a bearing on the bolt *i*, is adapted to bear in the normal position with its wall *k''* in contact with the substantially horizontal seat *m* forming the top surface of the head *c*, in which position the bend in the arm will be approximately coincident with the relatively outer extremity of said seat *m*. The arm is held in its normal position by a tie or tie-bar *n* having one end pivotally connected with the outer extremity of the arm and its other end secured to the pole *a* by a screw *o*. Upon removing the screw, the arm will be free to swing on the bolt *i* to the dotted line position shown in Fig. 1; that is, into closely folded relation to the pole, which movement may be allowed by cutting away or rounding the head *c* at the point *p*.

Removably secured in the angle between the walls *k'* and *k''* of the arm and at the free end of its major portion is a strip *q*, preferably of wood. Its securing means may be screws or the like *r*. From screw-eyes *s* set in this strip depends the tell-tales *t*.

As will be clear, by my construction, once the pole is in place, all operations attendant upon the installation or repair of the improved bridge-warning indicator can be effected without the workmen encroaching on the roadway. Further, should the arm be free for any reason to leave the normal or substantially horizontal position, it must fall to a position where it is not merely in partially folded (where it would interfere with traffic) but in fully folded relation to the pole.

By forming the tell-tale-carrying member *q* separate from the arm, that part of the device which immediately includes the tell-tales may be bodily removed for repairs.

Having thus fully described my invention, what I claim as new and desire to secure by Letters Patent is:—

1. In combination, an upright having a

bifurcated head formed as a substantially horizontal seat, a tell-tale carrying arm having an angular cross-section substantially from end to end thereof and including a longitudinal horizontal wall-portion and a longitudinal vertical wall-portion depending from said horizontal wall-portion and having its vertical wall-portion received in said head and pivoted therein on a horizontal axis and its horizontal wall-portion resting on said seat, said arm being gravity actuated to move normally into substantially folded relation to the upright, and means, connecting the arm and the upright, for holding the arm in the horizontal position, substantially as described.

2. In combination, an upright having a head formed as a substantially horizontal seat and provided with an upwardly open vertical slot, a bearing device extending horizontally through said head and traversing its slot, a tell-tale carrying arm having

an angular cross-section substantially from end to end thereof and including a longitudinal horizontal wall-portion and a longitudinal vertical wall-portion depending from said horizontal wall-portion and having its vertical wall-portion snugly received in the slot of said head and penetrated by and fulcrumed on the bearing device and its horizontal wall-portion resting on said seat, said arm being gravity-actuated to move normally into substantially folded relation to the upright, and means, connecting the arm and the upright, for holding the arm in the horizontal position, substantially as described.

In testimony whereof I affix my signature in presence of two witnesses.

HERBERT R. CAMPBELL.
